UNITED STATES PATENT OFFICE.

PIERRE B. NOYES, OF NIAGARA FALLS, NEW YORK, ASSIGNOR TO THE
ONEIDA COMMUNITY, LIMITED, OF KENWOOD, NEW YORK.

DESIGN FOR A SPOON.

SPECIFICATION forming part of Design No. 25,633, dated June 16, 1896.

Application filed May 4, 1896. Serial No. 590,232. Term of patent 31 years.

To all whom it may concern:

Be it known that I, PIERRE B. NOYES, a citizen of the United States, residing at Niagara Falls, in the county of Niagara, in the State 5 of New York, have invented and produced a new and original Design for Spoon and Fork Handles, of which the following is a specification, reference being had to the accompanying drawing, showing a part thereof.

10 This design relates to the ornamentation of spoon and fork handles, and the accompanying drawing represents a face view of a spoon embodying the design.

The leading feature of my design consists 15 of rows of beads extending along the margin of the handle and terminating at the outer end of the handle in scrolls and interrupted at the bulge of the handle by scrolls.

The handle has approximately the configuration 20 commonly known as the "fiddle outline." Along the edge of the handle extend two opposing rows of beads *a*, which inclose a plain field *b* and terminate at the junction of the handle with the shank *c*. The two 25 lines of beads are broken or interrupted at the bulge *d* of the handle by scrolls *e*, and at the enlarged outer end of the spoon the two lines terminate in similar scrolls *f*, between which is a short row of beads *g*, extending in-

wardly from the tip of the handle. The outer 30 scrolls *f* merge into lines *h*, which follow the inner sides of the rows of beads and extend to the inner scrolls *e*. *i* represents similar lines which extend along the inner sides of the beads on the bulge of the handle and terminate at the extreme inner end of the shank. On the inner portion of the shank, between the lines *i*, is a single row of beads *j*, extending nearly to the middle of the shank. The 35 beads on the outer enlarged portion of the 40 handle diminish in size from the outer scrolls *e* to the inner scrolls *f*, and those on the bulge of the handle diminish in size from the scrolls *f* toward the shank, while the beads on the inner portion of the shank increase in size toward the bowl of the spoon. 45

My design is applicable to fork-handles as well as spoon-handles.

What I claim is—

The design for the handle of a spoon or 50 fork, substantially as herein shown and described.

Witness my hand this 21st day of April, 1896.

PIERRE B. NOYES.
